UNITED STATES PATENT OFFICE.

ALFRED BUCOLO, OF WASHINGTON, DISTRICT OF COLUMBIA.

CUSHION-HEEL.

1,385,901.

Specification of Letters Patent. Patented July 26, 1921.

Application filed March 11, 1921. Serial No. 451,465.

To all whom it may concern:

Be it known that I, ALFRED BUCOLO, a subject of the King of Italy, residing at Washington, in the District of Columbia, 5 have invented new and useful Improvements in Cushion-Heels, of which the following is a specification.

The object of my present invention is the provision of a cushion heel possessed of 10 great suction capacity in addition to other practical advantages, and this notwithstanding the fact that the heel is susceptible of cheap production.

To the attainment of the foregoing, the 15 invention consists in the improvement as hereinafter described and definitely claimed.

In the accompanying drawings, forming part hereof:—

Figure 1 is an inverted plan view of a 20 cushion heel constructed in accordance with my invention.

Fig. 2 is a top plan view of the heel.

Fig. 3 is a longitudinal vertical section 25 showing the cushion heel as properly attached to the leather heel lifts of a shoe.

Fig. 4 is a transverse section of the cushion heel, taken in the plane indicated by the line 4—4 of Fig. 1.

Similar numerals of reference designate 30 corresponding parts in all of the views of the drawings.

In common with cushion heels at present in general use my novel cushion heel 1 is formed in one piece of vulcanized rubber or 35 other appropriate resilient material compatible with its purpose.

In its underside my novel heel 1 is provided with a vacuum chamber 2 which is preferably, though not necessarily, of stepped 40 formation and is closed at its top by the wall 3, this provision being advantageous inasmuch as the wall 3 is enabled to prevent water from reaching the lifts 4 of the shoe heel and deteriorating said lifts. The 45 heel 1 is also provided with nail holes 5 and with small suction chambers 6 which reach from the said nail holes 5 to the under surface of the heel. At its underside the heel 1 is provided with integral projections 7 and with an auxiliary suction chamber 8 the said chamber 8 being formed by the curvilinear rib 9 and the transverse rib 10. It will be understood by comparison of Figs. 1 and 2 that the projections 7 are arranged slightly in front of the transverse 55 median line of the heel, and the suction

chamber 8 is arranged at the rear of the heel, and by particular reference to Fig. 3 it will be noted that the projections 7 and the ribs 9 and 10 are of a common depth. 60 From this it follows that incident to the use of the new heel, the suction chamber 8 will be depended upon to prevent slipping of the heel on a wet surface, the projections 7 at that time enabling the ribs 9 and 10 to rest 65 squarely on the surface.

It will also be understood that after a few weeks of wear, the projections 7 and the ribs 9 and 10 will be worn away so that the surface 11 of the heel will be presented to a 70 pavement or the like. At this latter time the suction chamber 2 will come into play and will effectively prevent slipping of the heel on a wet pavement or other surface. By virtue of the provision of the projections 7 and the ribs 9 and 10 the heel is 75 adapted to be worn for a material time without any wear whatever of the body of the major portion of the heel, and from this it follows that the projections 7 and the ribs 9 and 10 are calculated to prolong the usefulness 80 of the heel considered as a unit. At its upper side the heel 1 is provided with a U-shaped marginal flange 12, the outer and inner corners of which are rounded as indicated by 85 13 and 14, respectively, Fig. 4, so that when the heel 1 is applied to a lift 4 and nails 15 are driven through the nail holes 5 and into the lifts 4, the portion of the heel 1 within the flange 12 will be carried to and snugly 90 held against the lowermost lift 4, and at the same time the edge portion of the heel 1 will be snugly crowded against the lowermost lift, with the result that a neat finish 95 will be produced and at the same time water will be prevented from entering between the cushion heel 1 and the lowermost lift 4. This will be better understood when it is stated that were the corners 13 and 14 sharp right angle corners, the compression of the heel 100 1 incident to its application to the heel lifts 4 would be attended by spreading of the flange 12 so that the uppermost portion of the heel 1 would be of greater area than the portion of the heel 1 below said uppermost 105 portion and in consequence the applied heel would not be as neat and finished in appearance as the heel characterized by the rounded corners 13 and 14. The edges of the heel 1 are preferably shaped as shown so that the 110 area of the underside of the cushion heel 1 will be slightly greater than the area of the

heel lifts 4 with the result that the cushion heel will be possessed of a large exposed surface.

Having described my invention, what I claim and desire to secure by Letters Patent, is:—

1. As a new article of manufacture, a cushion heel having in its underside a suction chamber closed at its top, and also having pendent projections spaced apart in front of the transverse median line of the heel, and an auxiliary suction chamber disposed in rear of the first-named suction chamber; the said auxiliary suction chamber being formed by pendent curvilinear and cross ribs, and the said projections and ribs being of a common height.
2. As a new article of manufacture, a cushion heel having in its underside a suction chamber closed at its top, and also having pendent projections spaced apart in front of the transverse median line of the

heel, and an auxiliary suction chamber disposed in rear of the first-named suction chamber; the said auxiliary suction chamber being formed by pendent curvilinear and cross ribs, and the said projections and ribs being of a common height, and the said heel also having at its upper side a U-shaped flange the outer and inner corners of which are rounded.

3. A cushion heel having at the underside of its rear portion a suction chamber and also having at its underside and spaced apart and in front of the suction chamber pendent projections; the said suction chamber being defined by a curvilinear rib and a connecting rib, and the said ribs and the said projections being of a common height, whereby the said suction chamber is adapted to serve until the ribs and pendent projections are worn away.

In testimony whereof I affix my signature.

ALFRED BUCOLO.
